UNITED STATES PATENT OFFICE

WILLIAM JOHN SPENCE, OF HAMILTON, ONTARIO, CANADA, ASSIGNOR TO GENERAL STEEL WARES LIMITED, OF TORONTO, ONTARIO, CANADA

RAILWAY LANTERN

Application filed November 8, 1929, Serial No. 405,686, and in Canada October 14, 1929.

This invention relates to lanterns of the type used by railway trainmen, and the object of the invention is to provide a reliable kerosene burning lantern which will burn under all the conditions to which such lanterns are subject, in heavy winds, rain and snow, close to locomotive whistles, and in the upright and inverted positions which are necessary in signalling.

The object is achieved by constructing a lantern of usual construction having a base, oil well, globe, globe holder or inner dome, an outer dome, breast, cage and bail, and providing vent holes in the base, in the outer dome and the globe holder adjacent the top of the globe. The oil well acts as a baffle for the vent holes in the base, the upper rim of the globe as a baffle for the vent holes in the lower part of the globe holder, and a baffle secured to the top of the globe holder shields the vents in the outer dome. In addition a horizontal slit is formed in the globe holder intermediate its ends, and an imperforate upwardly inclined annular baffle is secured to the globe holder below the slit. A perforate upwardly inclined annular baffle is secured to the globe holder above the slit, the inner ends of the two latter baffles converging and being joined together.

The invention is hereinafter more specifically described and illustrated in the accompanying drawings in which

Fig. 1 is a vertical section; and

Fig. 2 is a horizontal section on the line 2—2 in Fig. 1.

In the drawings corresponding numbers of the different figures refer to corresponding parts.

The lantern comprises a base 1 in which is set the oil well 2 to which is attached the burner 3. The globe 4 rests on the base 1 in a known manner. The globe is of standard size and shape such as is generally used in lanterns of this type.

The top of the globe is supported and held in position by the globe holder or inner dome 5 which is slidably mounted in the outer dome 6. A spring 7 is secured to the top of the globe holder, and is compressed against the top of the outer dome 6 and tends to re-

tain the globe holder 5 in contact with the globe 4. Strips 8 extend around the inside of the lower part of the outer dome 6, and have gaps therein as indicated at 9 through which lugs or pins 10 on the globe holder may be forced against the compression of the spring 7, and the globe holder by a twisting movement positioned so as to be retained in the dome, the strips 8 and pins 10 thus forming a sort of bayonet joint.

Extending outwardly from the base of the dome is the breast 11 which is hinged at one side to the cage 12 by hinge means 13, and is secured to the other side by a catch 14. A handle or bail 15 is connected to the cage 12. The cage is soldered to the base at 16.

The general construction of the base is well known. A series of perforations 17 are formed in the outside lower part thereof and admit air to the space between the oil well 2 and the outer wall of the base. A rim 18 is secured to the top of the base, and is provided with perforations 19 therein adjacent the top of the oil well 2, thus, providing connection between the interior of the globe and the space between the walls of the base 1 and the oil well 2. The rim 20 of the oil well 2 extends upwardly from the top thereof beyond the lower edge of the perforations 19, thus serving to deflect air passing through said perforations away from the burner 3.

The lower extremity of the globe holder or inner dome 5 extends some distance below the top of the globe 4, leaving a space therebetween. Perforations 21 are formed about the lower edge of the globe holder and below the upper edge of the globe 4, thus constituting the upper portion of the globe a baffle for shielding the burner from the direct inrush of air through the perforations 21 and also serving to intercept and force out through the perforations 21 any abnormal drafts coming down from the top of the lantern.

The globe holder or inner dome 5 is annular in form and extends upwardly in a convex curve for approximately half its height, forming a dome shaped roof 5^a for the combustion chamber of the lantern. At the top of the curved portion 5^a of the globe holder is a portion 5^b having perpendicular sides

which are adapted to slide within the outer dome 6, and to which the pins or lugs 10 already mentioned are attached. To the top of the perpendicular section 5^b is secured an 5 upwardly inclined annular baffle 22. This serves to break and intercept drafts coming through the perforations 23 in the top of the outer dome 6, and is located immediately below said perforations. Air intercepted by 10 the baffle 22 may pass out between the outer dome 6 and the perpendicular portion 5^b of the globe holder 5.

At the junction of the curved portion 5^a and the perpendicular portion 5^b of the globe 15 holder or inner dome 5 is a narrow horizontal slit 5^c extending all the way around the globe holder. Secured to the upper edge of the curved portion 5^a of the globe holder immediately below the slit 5^c is an upwardly 20 inclined annular baffle 24. This baffle is likewise convexly curved, and forms a continuation of the dome shaped roof of the combustion chamber. Secured to the sides of the perpendicular portion 5^b of the globe holder 25 immediately above the slit 5^c is another upwardly inclined annular baffle 25. The baffle 25 is provided with two rows of perforations 26, and the inner edges of the two baffles 24 and 25 converge, and are joined together. 30 Immediately below the baffle 24 and extending from side to side of the globe holder adjacent the top of the curved portion 5^a are a pair of straight baffle plates 27 which are parallel in a longitudinal direction, but which 35 converge in a perpendicular direction, the distance between the lower edges of each baffle being greater than the distance between the upper edges.

In operation this lantern has been shown 40 by test to withstand the most unfavourable conditions. When in an upright position, ample ventilation is provided by the perforations 17 and 19 in the base of the rim 20 and the oil well 2 deflects the in-coming air 45 away from the burner 3 sufficiently to prevent it from being disturbed or blown out. Gusts of air passing through the perforations 23 in the outer dome, either by wind or rapid motion of the air, or when the lantern is inverted are, as already mentioned, diverted by the baffle 22 which however permits the burnt gases and foul air from the burner to pass freely upward therethrough on ordinary occasions. Any excess air currents 55 which pass down through the perpendicular portion of the globe holder, which may be termed "the chimney", may be intercepted by the baffles 24 and 25, and caused to pass out through the slit 5^c to the atmosphere. This slit also provides extra ventilation when required, the baffle 25 tending to prevent too much air from either passing in or out of the slit 5^c. The baffles 27 are 60 commonly found in lanterns of this type, and 65 serve to direct the in-coming air currents

still more away from the flame. The use of the upper portion of the globe as a baffle for the perforations 21 is convenient, and simplifies the construction of the lantern. The perforations 21 provide extra ventilation, 70 particularly when the lantern is in an inverted position. It should be noted that according to this construction the upper part of the combustion chamber is dome shaped and has no obstructions thereon. In-coming 75 air from the top tends to flow around the walls of the combustion chamber and to pass down about the sides of the globe, keeping the globe cool, and keeping out of contact with the burner 3. The positioning of the 80 baffles 24 and 25 above the combustion chamber means that in-coming air from the top is deflected and directed outside of the lantern dome before the draft reaches the combustion chamber, thus providing better ventilation 85 and better protection for the light. In other known constructions baffles are provided within the lantern which merely deflect the drafts but do not dispose of them.

Although the form above described is preferred it should be understood that similar results may be obtained with the entire omission of the perforate baffle 25, or by the provision in the baffle 25 of some form of vent other than the perforations described. It 90 may also be possible to substitute a series of perforations or some other kind of opening for the slit 5^c, and it is not desired that the invention in its broad sense should be limited to the specific details of construction described in the specification and shown in the drawings.

What I claim as my invention is:

1. In a lantern, a base having vent holes 105 therein; a globe; an annular globe holder or inner dome having vent holes about its lower extremity, said globe extending upwardly within the holder to form an annular baffle adjacent the said vent holes; an outer dome in which the globe holder fits, said outer dome having vent holes adjacent the top thereof; an upwardly and inwardly inclined annular baffle at the top of the inner dome immediately below the vent holes in the outer dome; a slit in the sides of the inner dome extending around the said inner dome near the middle thereof, and below the lower extremity of the outer dome; an upwardly inclined annular baffle extending into the interior of the inner dome from the inside wall thereof 115 immediately below said slit; and a perforated upwardly inclined annular baffle extending into the interior of the inner dome from the inside wall thereof immediately above the slit, the inner edges 120 of said latter baffles converging and being joined together.

2. In a lantern, a burner; a base having vent holes therein; an oil reservoir in said base having an annular rim extending above 130

the lower edge of said vent holes to deflect air from the burner; a globe; an annular globe holder or inner dome having vent holes about its lower extremity, said globe extending upwardly within the holder to form an annular baffle adjacent the said vent holes; an outer dome in which the globe holder fits, said outer dome having vent holes adjacent the top thereof; an upwardly and inwardly inclined annular baffle at the top of the inner dome immediately below the vent holes in the outer dome; a slit in the sides of the inner dome extending around the said inner dome near the middle thereof, and below the lower extremity of the outer dome; an upwardly inclined annular baffle extending into the interior of the inner dome from the inside wall thereof immediately below said slit; and a perforated upwardly inclined annular baffle extending into the interior of the inner dome from the inside wall thereof immediately above the slit, the inner edges of said latter baffles converging and being joined together.

3. A lantern, having a combustion chamber having a dome-shaped roof; a chimney extending upwardly from the roof of the combustion chamber; a slit in the walls of the combustion chamber at the junction thereof with the chimney; an inclined curved annular baffle extending upwardly and inwardly from the inside wall of the combustion chamber immediately below the slit and comprising a continuation of the dome-shaped roof; and a perforate baffle extending inwardly from the inside wall of the chimney immediately above the slit, the ends of the two latter baffles converging and being joined together.

4. In a lantern, an outer dome; vent holes in the dome; an annular globe holder or inner dome having its upper part within the outer dome, and having a horizontal opening in its sides below the dome; an annular baffle extending inwardly from the inside wall of the inner dome immediately below said opening; and another annular baffle extending into the interior of the inner dome from the inside wall thereof immediately above the opening, the outer edge of each baffle being in substantially air tight contact with the globe holder.

5. In a lantern, an outer dome; a breast; vent holes in the outer dome; an annular globe holder or inner dome having its upper part within the outer dome, and having a horizontal opening in its sides below the outer dome and above the lower extremity of the breast; an annular baffle extending inwardly from the inside wall of the inner dome immediately below said opening; and another annular baffle extending inwardly from the inside wall of the inner dome immediately above the opening, the outer edge of each

baffle being in substantially air tight contact with the globe holder.

6. In a lantern, a globe; a dome having a horizontal opening in its sides above the globe; an annular imperforate baffle extending into the interior of the dome from the inside wall thereof immediately below said opening; and another annular baffle extending into the interior of the dome from the inside wall thereof immediately above said opening, the outer edge of each baffle being in substantially air tight contact with the inner wall of the dome.

7. In a lantern, a globe; a dome having a horizontal opening in its sides above the globe; an upwardly inclined annular imperforate baffle extending into the interior of the dome from the inside wall thereof immediately below said opening; and another annular baffle extending into the interior of the dome from the inside wall thereof immediately above said opening, the outer edge of each baffle being in substantially air tight contact with the inner wall of the dome.

8. In a lantern, a globe; a dome having a horizontal opening in its sides above the globe; an upwardly inclined annular imperforate baffle extending into the interior of the dome from the inside wall thereof immediately below said opening; and another annular baffle extending into the interior of the dome from the inside wall thereof immediately above said opening, said baffle having vent means therein, the inner edges of said baffle converging and being joined together and the outer edge of each baffle being in substantially air tight contact with the inner wall of the dome.

9. In a lantern, a globe; a dome having a horizontal opening in its sides above the globe; an upwardly inclined annular imperforate baffle extending into the interior of the dome from the inside wall thereof immediately below said opening; and a perforate annular baffle extending into the interior of the dome from the inside wall thereof immediately above said opening, the inner edges of said baffles converging and being joined together and the outer edge of each baffle being in substantially air tight contact with the inner wall of the dome.

10. In a lantern, a base; vent holes in the base; a globe; a dome having a horizontal opening in its sides above the globe; an annular imperforate baffle extending into the interior of the dome from the inside wall thereof immediately below said opening; and another annular baffle extending into the interior of the dome from the inside wall thereof immediately above said opening, the outer edge of each baffle being in substantially air tight contact with the inner wall of the dome.

11. In a lantern, a globe; an outer dome; vent holes in the outer dome; an annular globe holder or inner dome within the outer

dome having a horizontal opening in its sides above the globe; an annular imperforate baffle extending into the interior of the inner dome from the inside wall thereof immediately below said opening; and another annular baffle extending into the interior of the inner dome from the inside wall thereof immediately above said opening, the outer edge of each baffle being in substantially air tight contact with the inner wall of the dome.

12. In a lantern, a globe; an outer dome; vent holes in the outer dome; an annular globe holder or inner dome within the outer dome having a horizontal opening in its sides above the globe; an annular imperforate baffle extending into the interior of the inner dome from the inside wall thereof immediately below said opening; another annular baffle extending into the interior of the inner dome from the inside wall thereof immediately above said opening, the outer edge of each baffle being in substantially air tight contact with the inner wall of the dome; and a third inwardly extending annular baffle at the top of the inner dome immediately below the vent holes in the outer dome.

13. In a lantern, a globe; an annular globe holder or inner dome having a horizontal opening in its sides above the globe, and vent holes in its lower extremity adjacent the top of the globe; an annular baffle adjacent the vent holes; an annular imperforate baffle extending into the interior of the dome from the inside wall thereof immediately below the horizontal opening in the sides thereof; and another annular baffle extending into the interior of the inner dome from the inside wall thereof immediately above said opening, the outer edge of each baffle being in substantially air tight contact with the inner wall of the dome.

14. In a lantern, a base having vent holes therein; a globe; an annular globe holder or inner dome having vent holes about its lower extremity; an annular baffle adjacent said vent holes; an outer dome into which the inner dome fits, said outer dome having vent holes adjacent the top thereof above the top of the inner dome; an opening in the side of the globe holder intermediate its ends; an inclined annular imperforate baffle extending into the interior of the inner dome from the inside wall thereof immediately below the horizontal opening in the sides thereof; and another annular baffle extending into the interior of the inner dome from the inside wall thereof immediately above the said horizontal opening, the outer edge of each annular baffle being in substantially air tight contact with the inner wall of the dome.

15. In a lantern, a base having vent holes therein; a globe; an annular globe holder or inner dome having vent holes about its lower extremity; an annular baffle adjacent said vent holes; an outer dome into which the

inner dome fits, said outer dome having vent holes adjacent the top thereof, above the top of the inner dome; an opening in the side of the globe holder intermediate its ends; an inclined annular imperforate baffle extending into the interior of the inner dome from the inside wall thereof immediately below the horizontal opening in the sides thereof; and another annular baffle extending into the interior of the inner dome from the inside wall thereof immediately above the said horizontal opening, the upper of the two last mentioned baffles having vent means therein, and the inner edges of the upper and lower baffle converging and being joined together and the outer edge of each annular baffle being in substantially air tight contact with the inner wall of the dome.

Signed at Hamilton, Canada, this 29th day of October, 1929.

WILLIAM JOHN SPENCE.
